UNITED STATES PATENT OFFICE.

RUSSELL B. WILLIAMS, OF SCRANTON, PENNSYLVANIA.

RAILWAY SAFETY APPLIANCE.

SPECIFICATION forming part of Letters Patent No. 766,479, dated August 2, 1904.

Application filed April 9, 1904. Serial No. 202,344. (No model.)

To all whom it may concern:

Be it known that I, RUSSELL B. WILLIAMS, a citizen of the United States, residing at Scranton, in the county of Lackawanna and State 5 of Pennsylvania, have invented a certain new and useful Improvement in Railway Safety Appliances, of which the following is a specification.

The object of the present invention is to provide apparatus for guarding a car or train of cars when at rest both against unauthorized removal and against such removal, whether authorized or not, as would imperil railway employees at work upon the car or train—such, 10 for instance, as inspectors. Thus after a train has been run into the yard or train-shed after a trip it is customary for the inspector to forthwith examine the running-gear, this duty commonly taking him under the cars. 15 If now the locomotive having been detached when the train was brought to rest another locomotive should be coupled to the train to move it while the inspector was beneath one of the cars at work upon the running-gear, such 20 inspector would be exposed to grave danger.

In carrying out the invention in an approved form the safety-signal is applied to one of the rails at either end of the car or train. It comprises a clamping device for 25 the purpose of such attachment, which may include jaws hinged to each other and adapted to embrace the ball of the rail and suitable signals for both day and night use suitably attached to such jaws. Furthermore, the device 30 includes means for the application of a torpedo or torpedoes arranged in such relation to the rail as that should a locomotive approach the car or train an explosion would result, which would warn the inspector sufficiently in advance of the movement of the car or train to enable him to escape from a dangerous position.

The invention further contemplates the use of an appliance of the character described 45 which may be used in connection with rails of varying sizes, the jaws of the clamping device being provided with an adjustable locking mechanism, so that after the appliance has been set it may be locked in position to prevent unauthorized removal.

The invention is illustrated in the accompanying drawings, in which—

Figure 1 is a side elevation of the safety appliance attached to a rail. Fig. 2 is an enlarged end elevation, the signals and their 55 supporting-shafts being detached. Fig. 3 is an enlarged cross - section illustrating one form of locking mechanism for attaching the hinged jaws securely together; and Fig. 4 is a top plan view on the line 4 4, Fig. 2. 60

Referring to the drawings, in which similar letters denote corresponding parts, A designates a rail of common form, and B the clamping mechanism of the safety appliance. (Shown in position relatively to such rail in 65 Figs. 1 and 2.) Said clamping mechanism is here shown as comprising the jaws C D, hinged together by means of the pivot-pin c. The lower portions of said jaws C D are provided with the inturned ends c' d, adapted to 70 coact with the under side of the ball of the rail, the construction of said jaws below the pivotal point being such as to embrace the ball of the rail and clamp the same firmly against accidental displacement. The upper 75 ends of said clamping-jaws C D are here shown as provided with sockets c' d', each of which is adapted to receive and support a shaft c' d', the former carrying at its upper end the flag or day-signal c' and the latter 80 carrying at its upper end the lantern or night-signal d'.

The clamping mechanism B will preferably be constructed of pressed steel or other suitable durable material. The shafts c' d' of the 85 day and night signals may, if desired, be of wood or other material.

It is of course desirable that after a car-inspector shall have secured his safety appliance in position at one or both ends of the train 90 the same shall not be interfered with by an unauthorized person, thereby leaving the inspector unguarded. For this purpose any suitable locking mechanism may be employed—as, for instance, a lock between the clamping-jaws 95 C D, and because of the considerable variation in the sizes of rails in common use such a locking device must be adjustable. One form of lock meeting this requirement is illustrated in detail in Fig. 3, in which the jaws C and 100

D are shown as provided with housings c^5 d^4 , respectively. The clamping-jaw D is provided with an adjustable bolt F, having a hook-shaped inner end f', the body of said bolt being screw-threaded and passing through nuts f^1 and f^2 by means whereof the degree of projection of the end f' of said bolt may be readily determined. Within the housing c^5 is located the locking mechanism proper, the same comprising the locking-tongue G, hinged at g and provided with an actuating leaf-spring g'. Immediately below the locking-tongue G may be arranged a keyhole g², extending entirely through the housing c^5 , as illustrated in Fig. 2. As will easily be understood, upon the introduction of the key into the keyhole g² the locking-tongue G may readily be raised to free the same from the hook-shaped end f' of the bolt F. At the same time the engagement of said locking-tongue G with said bolt F is automatic, it being necessary only to move the clamping-jaws together for this purpose.

E designates a wing secured to or formed integral with any suitable part of the appliance. It is here shown as formed integral with the jaw D of the clamping mechanism and extends outward substantially at right angles to the upper vertical portion of said jaw, so as to directly overlie the top of the rail A.

e designates torpedoes which may be placed upon said wing E, the leaden ribbons or straps of said torpedoes being bent around the edges of such wing, as clearly shown in Fig. 2.

In practice a safety appliance such as that above described should be clamped to the rails by the inspector at both ends of the car or train at rest and at a suitable distance—say 40 from fifty to one hundred feet—therefrom. Should a locomotive-driver ignoring the signals carried thereby run his engine toward the car or train for the purpose of coupling to the same, he would first have to demolish the 45 appliance and in so doing would explode the torpedoes E, thereby giving sufficient warning to the inspector to escape from beneath the car or train, as above explained.

I do not desire to limit myself specifically 50 to the details of the mechanism hereinabove described, as the same may be varied without departing from the invention. Particularly is this true with respect to the locking mechanism of which I have attempted to show no 55 more than a suggested form adapted to meet the requirements above stated.

Having now described my invention, what I claim as new therein, and desire to secure by Letters Patent, is as follows:

60 1. In a railway safety appliance, the combination with a rail, of a clamping device, a signal supported thereby, and a wing or sup-

port carried by said appliance for exposing a torpedo to the contact of a wheel operating upon said rail, substantially as set forth. 65

2. In a railway safety appliance, the combination with a rail, of a clamping device, including hinged and relatively movable jaws, and a day-signal and a night-signal supported thereby, substantially as set forth. 70

3. In a railway safety appliance, the combination with a clamping device including jaws hinged together and adapted to be detachably secured to the ball of a rail, of a locking device for said jaws, and means for supporting a signal or signals in said jaws, substantially as set forth. 75

4. In a railway safety appliance, the combination with hinged jaws whose lower ends are adapted to coact with a rail and whose upper ends are adapted to support a signal or signals, of a wing carried by one of said jaws and overlying said rail, substantially as set forth. 80

5. In a railway safety appliance, the combination with hinged jaws adapted to coact with a rail, of sockets carried by the upper ends of said jaws and adapted to support a signal or signals, substantially as set forth. 85

6. In a railway safety appliance, the combination with hinged jaws whose lower ends are adapted to coact with a rail, of a locking device for automatically locking said jaws in position after attachment to such rail, substantially as set forth. 90

7. In a railway safety appliance, the combination with hinged jaws whose lower ends are adapted to coact with a rail and whose upper ends are provided with a means for supporting a signal or signals, of a locking device for securing said jaws in a predetermined position, and a wing carried by one of said jaws and directly overlying said rail, said wing being adapted to support a torpedo, substantially as set forth. 95

8. In a railway safety appliance, the combination with hinged jaws adapted to coact with a rail and to support a signal or signals, of an adjustable locking device coacting with said jaws, substantially as set forth. 100

9. In a railway safety appliance, the combination with hinged jaws adapted to coact with a rail and to support a signal or signals, of locking mechanism automatically thrown to operative position by the attachment of said 105 jaws to said rail and manually thrown to inoperative position, substantially as set forth.

This specification signed and witnessed this 28th day of March, 1904.

RUSSELL B. WILLIAMS.
